UNITED STATES PATENT OFFICE.

HENRY R. GARRITSON, OF LOGANSPORT, INDIANA.

SHIPPING-CRATE.

1,329,966.

Specification of Letters Patent.

Patented Feb. 3, 1920.

Application filed June 11, 1919. Serial No. 303,389.

To all whom it may concern:

Be it known that I, HENRY R. GARRITSON, a citizen of the United States, residing at Logansport, in the county of Cass and State 5 of Indiana, have invented certain new and useful Improvements in Shipping-Crates, of which the following is a specification.

This invention relates to shipping crates, particularly to those of the round basket 10 type, and has for its object the provision of an improved form of shipping crate in which the bottom is formed integrally upon the ends of the staves whereby the crate will embody in its construction the minimum number 15 of parts, the bottom members on the staves being secured by common fastening members.

With the above and other objects and advantages in view, the invention consists in 20 the details of construction to be hereinafter more fully described and claimed, and illustrated in the accompanying drawing, in which

Figure 1 is a vertical, longitudinal section, taken on line 1—1 of Fig. 2.

Fig. 2 is a horizontal section on line 2—2 of Fig. 1.

Referring more particularly to the drawing, I have shown my crate as formed of a 30 plurality of staves 10 which are formed as flat strips of wood as this is the commonest material employed in the construction of crates of this character. In the construction of the crate the staves are transversely scored 35 and bent to form L-shaped members, the vertical arms of which constitute the staves proper of the crate, and the horizontal arms 11 of which, when properly connected, constitute the bottom. The staves are arranged in pairs, as clearly shown, with the 40 horizontal arms 11 thereof superposed and secured together by common fastening members 12 which may be nails, staples, rivets, or the like.

At the bottom of the crate I provide external and internal hoops 13 and 14, respectively, which are secured to the vertical portions of the stave members and to each other by staples, nails, or the like. At points 45 throughout the height of the crate I also provide external hoops 15 and at the upper extremities of the staves I also provide an internal hoop 16 which is secured to the staves and to the uppermost outer hoop 15.

As additional reinforcing means, I provide

a wire member 17 which extends diametrically across the bottom and which has its ends secured through the external and internal hoops 13 and 14, the ends being secured in any suitable manner, as for instance 60 by twisting around the hoops.

From the foregoing description and a study of the drawing it will be apparent that I have thus provided a very simply constructed crate in which the bottom and sides 65 are formed integrally whereby the structure will embody the minimum number of parts and whereby the cost of production will be very little. It will also be observed that, owing to the provision of the various hoops 70 as well as the transverse wire member, the structure will be amply reinforced so as to insure the proper degree of strength for holding up during transportation.

Having thus described my invention, I 75 claim:

1. In a shipping crate including a plurality of substantially vertically extending staves, lateral extensions formed integrally upon the lower ends of said staves and secured together to constitute the bottom of the crate, and a wire member extending diametrically across said bottom with its ends secured to said extending staves. 80

2. In a shipping crate including a plurality of substantially vertically extending staves, lateral extensions formed integrally upon the lower ends of said staves and secured together to constitute the bottom of the crate, hoops secured at intervals throughout the length of the vertical extending staves, and reinforcing means extending diametrically across the bottom and secured at opposite sides thereof to the lowermost 90 hoop. 95

3. In a shipping crate including a plurality of substantially vertically extending staves, lateral extensions formed integrally upon the lower ends of said staves and secured together to constitute the bottom of the crate, hoops secured at intervals throughout the length of the vertical extending staves, and a wire member extending across the bottom at the underside thereof and secured at its ends to the lowermost hoop. 100

In testimony whereof I affix my signature.

HENRY R. GARRITSON.

Witnesses:

EDITH MATT,
CRYSTAL KINGERY.
